UNITED STATES PATENT OFFICE.

SAMUEL SOBEL, OF SEAGATE, NEW YORK.

DESIGN FOR A PEDESTAL FOR DISPLAY FIXTURES.

Application filed May 12, 1923. Serial No. 6,147. Term of patent 3½ years.

To all whom it may concern:

Be it known that I, SAMUEL SOBEL, a citizen of Russia, residing at Seagate, in the county of Kings, State of New York, have invented a new, original, and ornamental Design for a Pedestal for Display Fixtures, of which the following is a specification, reference being had to the accompanying drawing, forming part thereof.

Figure 1 is an elevation of the pedestal showing my new design.

Figure 2 is a section on the line 2—2 of Figure 1.

I claim:

The ornamental design for a pedestal for display fixtures, substantially as shown.

SAMUEL SOBEL.
